UNITED STATES PATENT OFFICE

ALBERT HENRY MEIER, OF EVANSVILLE, INDIANA

PIPE VISE AND BENDER

Application filed December 7, 1927. Serial No. 238,284.

This invention relates to improvements in pipe vises and benders and, more particularly, to improvements on the pipe vise and bender set forth in my Patent No. 1,688,199, dated Oct. 16, 1928.

The present improvements comprise a saddle attachment which may be applied to, or removed from, the base of the appliance, and chains connected to the base and adapted 10 to be made to encircle a tree, telegraph or telephone pole, post, piece of studding, or other object, whereby the pipe vise and bender may be secured in position, ready for use at the place where work is to be done, 15 thus obviating the necessity of providing a bench or the like, as has been customary.

When the object is cylindrical, for instance a telephone or telegraph pole, the saddle is used but when the object is square, 20 the saddle may be detached from the base of the pipe vise and bender and the base and chains used to hold the appliance in position.

Other improvements reside in the provision of a cut-out part or notch adjacent the 25 seat for the fixed jaw so that when it is necessary to make a bend at the extreme end of the pipe or conduit, the pipe or conduit coupling may be accommodated, the fixed jaw having previously been removed; a bending yoke which has an integral stub or projection over which a section of pipe may be 30 fitted for use as an operating handle; constructing the bending form as a skeleton, to lighten the weight; and other improvements 35 which appear more fully hereinafter.

A practical embodiment of the invention which has been found to be successful is shown in the accompanying drawings, in which:

40 Figure 1, is a plan view showing the appliance applied to a round post or pole, the pipe being in its initial position;

Fig. 2, is a similar view, showing the post or pole and the saddle and base in section, 45 the pipe being shown as bent;

Figure 3, is a view showing the appliance connected to a square post or to a bench, dotted lines representing the yoke of the vise in its opened position;

50 Fig. 4, is a side elevation of the appliance

when applied to a post or pole as shown in Fig. 2;

Fig. 5 is a side elevation showing the appliance attached to a bench or square post, the saddle having been removed;

Fig. 6, is a section on the line 6—6, Fig. 4;

Fig. 7, is a section on the line 7—7, Fig. 4;

Fig. 8, is a detail perspective view of the saddle; and

Fig. 9, is a similar view of the removable jaw.

The brackets and bending form are cast in a single piece as a malleable casting, said brackets 1 and 2 being arranged at right angles to each other so that the appliance may be fastened by bolts or screws to a bench or other support used in a shop or where a suitable horizontal support is available, one or the other of the brackets enabling the appliance to be positioned most conveniently for use.

Holes 3 are provided in the brackets and in a web of the form for the accommodation of the necessary bolts or screws.

Instead of providing a form which has a complete web, the form is substantially skeleton as shown at 4 and is provided with ribs 5 which provide the necessary strength, whereas the skeleton form lightens the weight.

The groove 6 in the form is for the accommodation of the rod, pipe, tube, or conduit which is to be bent, and said groove is laid out on a curve, as usual in pipe benders.

The pipe bending lever comprises a yoke 7 which straddles the form and is pivoted on a removable pin 8 which passes through the hub of the form, suitable retaining means such as cotters 9, being used to prevent displacement of the pin.

The yoke has another pin 10 which may be removable, or headed down at 11, said pin constituting an axle for the grooved bending wheel or roller 12.

Instead of having a socket, as proposed in my aforesaid patent, the yoke is provided with an integral stub handle 13 which is of a size adapting it to removably fit into a section of pipe 14 which may be as long as desired and which will serve as an operating

90

100

lever or handle. The tubular operating handle or lever 14 may be removed when it is not required, thus removing from the appliance a part which might interfere with the use of the vise now to be described.

5 If desired, the pin 8 may be removed so that the yoke can be taken off when the vise is to be used.

10 There are lugs or ears 15 which project from opposite sides of the body parallel to the bracket, said ears and bracket having holes to accommodate a pin 16 by which the frame 18 has one of its legs pivoted to the body, enabling the frame and the device carried thereby to be swung aside as shown by dotted lines (Fig. 3).

15 The vise has a screw 20 threaded through its cross-piece and it is provided with a pivoted handle 21, said handle being adapted 20 to be turned crosswise of the screw and used as a lever for turning the screw, or, disposed in extended relation to the screw. There is a movable head 23 which slides on, and is guided by, the legs of the yoke. A 25 steel jaw 24 is removably connected to the head by screw bolts 25, enabling steel jaws of other sizes to be substituted for the steel jaw 24, if desired.

20 For the purpose of securely latching the 30 free part of the yoke without having to resort to the use of a locking pin, there is provided a hook or latch 35 which is pivoted to the yoke 18 at 36 and is adapted to engage and lock with the sloping shoulder 35 37 on the body 4.

25 On releasing the hook 35 from the shoulder 37, the yoke 18 can be swung back, as shown in dotted lines, to permit quick removal of the bent or threaded pipe or the like. The yoke can then be quickly re-latched, as shown in full lines.

30 For the purpose of securely clamping the pipe, the tube, or the like which is to be bent, threaded or cut off, I provide a stationary, but removable, steel jaw 30 (Fig. 9) 45 to match up with the jaw 24, said jaw being secured in line with jaw 24 by bolts passing through holes 32 in the jaw 30 and holes 33 (Fig. 6) in the body. This fastening, like 50 that shown at 25 for the jaw 24, enables the jaw 30 to be removed for replacement, reshaping, substitution, etc.

35 To enable a pipe or tube or conduit to be bent close to its end and to accommodate 55 a pipe coupling and section of pipe which have to be provided in such an operation, I have provided a semi-circular cavity 39 at the inner end of the groove 6 in the bending form and a semi-circular notch 40 in the 60 bracket, (Figs. 4 and 7). This cavity and notch are adapted, respectively, to accommodate a pipe coupling 41 and a pipe section 42 which are attached to the piece of pipe 43 which is to be bent.

65 When it is necessary to bend the pipe 43

right down to its end, the coupling and the pipe section aforesaid are attached to the pipe 43 and the jaw 30 is removed from its holder or socket 34. Accommodation having thus been provided for the pipe coupling and pipe section, the end of the pipe 43 can be located in the end of the groove 6 so that the roller 12 can act clear down to the end of the pipe 43.

70 When a bend is to be made in an intermediate part of the pipe 43, it is not necessary to use the pipe coupling or extra section aforesaid but the pipe itself is directly gripped by the jaws 24 and 30.

75 In any instance, however, where a bending operation is to be performed, the jaw 24 will be used to grip the pipe, or the coupling, as the case may be.

80 Should it be desired to use the vise by itself to hold a pipe, tube, conduit, or rod, for the 85 purpose of cutting it off or screw threading it, the article will be clamped by the jaws 24 and 30 and in that event, the pipe handle 14 may be removed, or even the yoke 7 taken off so that there will be no parts in the way 90 to interfere with the operation.

85 To enable the appliance to be secured to a round post, or telegraph or telephone pole so that it may be readily used in many locations where a bench or horizontal support 95 is not available, the following improvements are provided.

90 A saddle 44 which has curved, spaced seats 45 adapted to fit the pole or post, and has notched or bifurcated ends 46, is detachably 100 secured to the base. Preferably, the saddle has elongated slots 47 through which pass bolts 48 extending through the base of the appliance. The bolts 48 enable the saddle to be adjusted lengthwise of the base so that 105 the vise and the bending apparatus may be properly disposed according to circumstances and enable the saddle to be quickly attached or removed.

95 To enable the appliance to be suspended 110 prior to permanently fastening it on the pole or post, a hole 49 is provided in one of the seats 45 and through this hole there may be driven a nail 50 as shown in Figs. 1 and 8.

105 The means for fastening the vise and 115 bender in position on the post or pole comprises chains 51 suitably connected to the base of the appliance as, for instance, by an eye bolt 52 and a yoke 53.

110 An adjustable connector is used for attachment to the free ends of the chains 51, said connector comprising a bearing plate 54 having a hook 55 to engage any desired link of 115 one of the chains, and a hook bolt 56 to engage any one of the links of the remaining chain, said hook bolt having its screw threaded shank slidably mounted in the eye 57 and provided with a nut 58 by which it may be tightened or loosened.

120 When applying the pipe vise and bender to 130

a square post, it may be directly connected thereto by screws or spikes driven through the holes 3, the saddle 44 being taken off.

When the appliance is connected to a round post or pole, the saddle 44 is applied thereto, the nail 50 being driven through the hole 49 and into the post or pole to suspend the appliance while the chains are being tightened. A link of one of the chains is then engaged with the hook 55 and after the slack has been taken up, a link of the other chain 51 is engaged with the hook bolt. The nut 58 is then screwed up until the chains are tight around the pole or post.

What I claim is:

1. The combination with a pipe, rod, conduit, or tube bender and vise having a base, of a saddle detachably connected to said base, enabling said saddle to be utilized or removed, separate chains each connected to the base and adapted to be passed around a pole or post, and an adjustable hook connector for detachably and adjustably connecting together the free parts of the chains.

2. The combination with a pipe, rod, conduit, or tube bender and vise having a base, of a saddle detachably connected to said base, enabling said saddle to be utilized or removed, separate chains each connected to the base and adapted to be passed around a pole or post, an adjustable hook connector comprising a bearing plate having an eye and provided with a hook adapted to engage a link of one of the chains, and an adjustable hook bolt provided with a nut, the shank of the bolt being slidable through the eye and the hook of said bolt being engageable with a link of the remaining chain, said connector being adapted to detachably and adjustably connect together the chains around the pole or post.

3. In a pipe, rod, conduit, or tube bender and vise, the combination with a body having a bending form provided with a groove and with an enlarged cavity adapted to receive a pipe coupling on the pipe, rod, conduit, or tube to be bent, whereby the bend may be made at the end of said pipe, etc., and also having a socket or receiver into which one side of said cavity opens, the opposite wall of the cavity being provided with a notch adapted to receive another pipe section connected to the coupling, means for clamping said pipe, etc., and means for bending said pipe, etc.

4. In a pipe, rod, conduit, or tube bender and vise, the combination with a body having a bending form provided with a groove and with an enlarged cavity adapted to receive a pipe coupling on the pipe, rod, conduit, or tube to be bent, whereby the bend may be made at the end of said pipe, etc., and also having a socket or receiver into which one side of said cavity opens, the opposite wall of the cavity being provided with

a notch adapted to receive another pipe section connected to the coupling, a removable jaw adapted to be located in said cavity, a pipe vise having an adjustable jaw and means for operating said adjustable jaw, said adjustable jaw being adapted for use alone to secure the pipe when a coupling is used, or, said removable jaw being adapted for use in connection with the adjustable jaw to clamp a pipe when no pipe coupling is used, and means for bending the pipe.

5. In a pipe, rod, conduit or tube bender and vise, the combination with a body having a bending form, and movably mounted bending means carried by said body, of a saddle carried by said body having oppositely disposed notches or bifurcations, independent chains connected to the body and adapted to enter the respective notches or bifurcations, and means for tightening the free parts of said chains.

6. In a pipe, rod, conduit or tube bender and vise, the combination with a body having a bending form, and bending means carried by said body, of a saddle carried by said body having oppositely disposed notches or bifurcations, separate chains separately connected to the body and adapted to enter the respective notches or bifurcations, and a multiple-part adjusting device directly connecting together the free ends of said chains for drawing together or letting out said chains and for securing said chains around a pole or post.

In testimony whereof I affix my signature.

ALBERT HENRY MEIER.
